WIRED NEWS DISSEMINATING SYSTEM

Harold F. May, Valley Stream, N. Y., assignor to
The Teleregister Corporation, New York, N. Y.,
a corporation of Delaware

Application June 3, 1938, Serial No. 211,535

9 Claims. (Cl. 179—1)

This invention relates to a wired news disseminating system, and more particularly to a system for disseminating information, such as stock averages and other market news, and for interspersing additional information, such as news flashes, for transmission to a plurality of subscribers' stations.

The principal object of this invention is to provide a system of the character described, where 10 in messages originating at a main station are to be audibly received simultaneously and selectively at a plurality of outlying stations connected by means of line conductors radiating from the main station, the arrangement of the equipment 15 according to this invention being especially applicable to the distribution of stock quotations, news items or other matter in connection with market averages and information relating to an investment service.

20 In general this system provides a method whereby signaling and communication operations may be carried on between the main station and the outlying stations in a manner to render the subscribers' equipment responsive to line signals 25 for broadcasting of special items and selectively responsive under control of a device at each subscriber's station for suppressing the reception of other broadcast signals by the subscriber's equipment.

30 This system also provides that the main station may signal or communicate with any of the outlying stations selectively under control of a manually settable device at each of the outlying stations, all in a manner to effectively reproduce all 35 of the communication signals received at certain of the outlying stations and to prevent certain of the communication information from being reproduced at others of the outlying stations, depending upon the setting of the manually controlled device.

In order that the advantages of the present system may be more readily understood, the more important service features desirable in a system of this character will first be briefly considered. 45 In connection with the regular transmission of information relating to stock transactions, as for example, the price of the transactions or the amount of the sale, stock averages and the like, it frequently transpires that important news 50 items are received at the main station from which point such items should be immediately transmitted to the outlying stations in precedent of less important quotation information. In the handling of press traffic such important items 55 are commonly referred to as "flashes". In a sys-

tem of the character herein described it is important that a suitable switching device at the outlying station be operated by the central station attendant immediately preceding or coincident with the transmission of the more important 5 news items, for which the transmission of the less important quotation information would, of course, be interrupted. Such a method of call signaling insures that a special news item will be received and reproduced at each outlying station 10 irrespective of the setting of the manual device at the station even though the device is set in a position to cause the quotation information signals to be prevented from normally operating the sound reproducing element in the outlying station. 15

In carrying out the present invention a preferred arrangement is based on the employment of equipment to permit simultaneous telephone services over each of several circuits which may 20 radiate from a main station to an outlying or substation. The quotation information signals are carried on over a metallic loop or pair of conductors, whereas the signals controlling the operation of the switching device in the outlying 25 station for the transmission for news flashes is worked phantom over such line pairs.

A further object of the invention is the provision of an audio amplifying system having a combination of two or more sets of audio circuits, 30 units and transformers, a plurality of receiving equipments each comprising a loud speaking receiver or other voice reproducing element adapted to be operatively connected to an audio amplifying unit within the receiving apparatus either 35 by means controlled by the attendant at each outlying station or by a device controlled by the announcer at the central station.

Another object of the invention resides in the provision of means operable at will for adjusting 40 the impedance of the system in accordance with the number of outlying stations connected thereto.

This invention is illustrated diagrammatically in the accompanying drawings in which only so 45 much of the telephonic and flash signal equipment is shown as will be necessary to a clear understanding of the system.

Referring to the drawings, Fig. 1, illustrates an arrangement at the main station in which the 50 telephone working and flash signal operation may be carried out in accordance with one embodiment of the invention. In Figs. 2 and 3 is shown the signal repeating and amplifying circuits controlled by the arrangement of Fig. 1. In Fig. 4 is 55

shown a plurality of subscribers' equipment in diagrammatic form including one such equipment in circuit detail.

- Referring first to Fig. 1, there is shown thereon a microphone 1 connected by a cord 2 to a plug 3 adapted to be inserted into a jack 4 connected to the input circuit of a microphone amplifier MA and to the contacts of a tone control key TK. The output of the microphone amplifier is connected to contacts of the relay S in such a manner that when the relay S is unoperated an artificial load is placed across the output of the microphone amplifier and when the relay S is operated the artificial load is removed and the output of the microphone amplifier is connected through an attenuator to the input of a buffer amplifier BA and to the input of a repeater amplifier RA2, Fig. 2, preferably located at the main station.
- 20 A power supply unit PS supplies current to the heater filaments of the amplifying tubes of the microphone and buffer amplifiers and rectified current to the plates of these tubes.

The output of the buffer amplifier is connected by way of two pairs of conductors to a switch at a repeater station RS which may be remote from the buffer amplifier at the main station. The repeater station includes a repeater amplifier unit RA1 having the output thereof connected to the input of one or more line coupling units, there being one such line coupling unit for each subscriber's loop. A power supply unit PS1 supplies suitable current for the heater filament of the repeater amplifier tubes and rectified current for the plates of these tubes.

The subscriber's equipment shown in detail of Fig. 4 on the drawings comprises a flash relay SFL and a subscriber amplifying unit SA having the input thereof connected to the conductors comprising the subscriber's loop. The output of the subscriber's amplifying unit is connected to a loud speaking receiver, the circuit being closed by the control key CK or by the operation of the flash relay SFL, as the case may be. The subscriber's amplifying unit comprises two tubes in push-pull arrangement preferably for operating the loud speaking receiver. These tubes receive their filament heating current from the subscriber's power supply unit SPS which also supplies the plate current necessary for the operation of the tubes. The subscriber's power supply unit may be connected to a source of either alternating or direct current, thereby rendering the subscriber's equipment suitable for operation in areas regardless of the type of current available.

The operation of the system will now be described: The key SK is operated thereby applying ground to one end of the winding of the relay S and causing it to operate. The operation of relay S at its armature 5 applies battery to the lamp SL causing the lamp to light as an indication that the microphone amplifier is connected to the buffer amplifier BA, Fig. 1 and repeater amplifier RA2, Fig. 2. The key TK is moved to the "off" position and the microphone is plugged into the microphone amplifier by the insertion of the plug 3 into the jack 4 before the key SK is operated. Voice currents from the microphone 1 pass through transformer 6 into the amplifying tube 7 and thence through transformer 8, amplifying tube 9 and transformer 11 through the conductors 12 and 13 to the decibel meter DB, the circuit being closed from conductor 13 through 75 the decibel meter DB, contacts 14 of the key TK

to conductor 12. Conductor 13 is also connected to armature 15 of relay S from whence the circuit is continued through the make contact thereof, one winding of the transformer 16, conductor 17, armature 18 and make contact of relay S to conductor 12. The voice currents from the transformer pass through the amplifying tubes 19 and 21 and thence to the transformer 22 of the buffer amplifier. Transformer 22 is provided with two secondary windings connected by way of conductors 23 and 24 to the contacts of a switch 25 located at the repeater station RS whereby the repeater station receives signals over the conductors 23 or 24 in accordance with the position of the switch 25.

The circuit to the switch 25 is continued by way of conductors 26 to a transformer 27 and thence through the repeater amplifier tubes 28 and 29 to the transformer 31. The circuit is continued through the transformer 31, taps 32, slip connections 33 and conductors 34 to the windings of transformer 35 comprising the various line coupling units. The circuit is continued through transformer 35 by way of taps 36, slip connections 37, balance resistances 38, conductor 39, condenser 41, potentiometer 42 and transformer 43 from whence the circuit is continued through the subscriber's amplifying tubes 44 and 45 to the transformer 46, the secondary winding of which is connected by way of conductor 47 to 30 the voice coil of the loud speaking receiver 48 and thence by way of conductor 49 to a contact of the key CK and armature 51 of the relay SFL. With the relay SFL or the key CK operated, the circuit is continued by way of conductor 52 to 35 the other end of the secondary winding of the transformer 46.

It will be assumed that the subscriber has closed his key CK and the switch 53, thereby connecting power to the subscriber's power supply 40 unit and thus preparing his equipment for the reception of broadcast signals.

With the subscriber's control key CK in the closed position, a connection is established between the subscriber's amplifying unit and the 45 loud speaking receiver whereby the receiver is responsive to all messages originating at the main station. In the event that the subscriber does not care to receive all messages on his loud speaking receiver, the key CK is opened and his receiver is thereby placed in condition to respond to only those messages which comprise news flashes. The operation of the system to transmit a news flash will now be described.

When the announcer at the main station desires to transmit a news flash, he depresses the flash key FL, Fig. 1, thereby connecting ground to conductor 54 and causing the news flash relay NF, Fig. 2, to operate and at its armature 55 apply battery to conductor 56 and cause the news 60 flash lamp NFL to be lighted as an indication to the announcer that the system is in condition to transmit a news flash. When armature 57 of relay NF engages its make contact, battery is applied to conductor 58, resistors 59, secondary 65 windings of the transformer 22 and thence to the line conductors 23 and 24 from whence the circuit is continued by way of the switch 25 in circuit with the conductors 23 or 24 as the case 70 may be, and thence to the windings of the repeater flash relay RFL, Fig. 3, the other end of the relay windings being connected to ground. The relay RFL at the repeater station operates over the circuit just described and at its armature 75 applies battery to conductor 62, resistance 63

and slip connections 64 of each of the line coupling units. The circuit is continued from slip connections 64 through the secondary windings of transformer 35 of the line coupling unit, 5 balance resistances 38 and by way of line conductors 39 to the windings of the subscriber's flash relay SFL and thence to ground, thereby causing relay SFL to operate and at its armature 51 connect the voice coil of the loud speaking 10 receiver 48 to the secondary winding of the transformer 46 of the subscriber's amplifying unit of each of those installations where the control key CK is unoperated. The loud speaking receiver 48 is thus placed in operative relationship with 15 the subscriber's amplifying unit whereby the flash announcement is audibly received by the subscriber's equipment. When the news flash announcement has been made, the announcer restores the flash key FL at the main station causing 20 the subscribers' flash relays SFL to be released and disconnect the loud speakers from the subscriber amplifying units.

When it is desired to disconnect power from the subscriber's equipment at the outlying stations, as for example, at the conclusion of the broadcast service, the system functions to accomplish this result in the following manner: The tone control key TK at the main station is moved to the "on" position and at its contact 65 25 applies ground to conductor 54 to cause the subscribers' flash relays SFL to operate and at their armatures 51 connect the loud speakers 48 to their respective transformers 46 thus insuring that all outlying stations will audibly reproduce 30 the disconnect signal which is about to be transmitted. As the switch TK was moved to the "on" position, the circuit to the meter DB was opened at contact 14 of the key to prevent damage to the meter from the signal tone which is preferably 35 of greater strength than the microphone signals employed with the system. The operation of relay TK at its contact 66 applies ground to the winding of the relay S causing the relay to operate and at its armature 15 disconnect the artificial load 67 from the output of the microphone 40 amplifier and establish a connection between the output of the microphone amplifier and the buffer and repeater amplifiers BA and RA2, respectively. With the key TK moved to the "on" 45 position, ground is applied by way of contact 68 of the key TK to conductor 69 extending to winding 1 of relay A from which point the circuit is continued through the winding of relay A, resistance 71, conductor 72 and thence to battery, thereby causing relay A to operate. As 50 armature 73 of relay A engages its make contact, the winding 1 thereof is short circuited causing the relay to release and immediately reoperate as soon as armature 73 is disengaged from its 55 make contact. The resistance 71 is employed to protect the circuit from an excess of current when winding 1 of relay A is short circuited. Relay A continues to operate and release in rapid succession and produce a tone signal through 60 its winding 2 for transmission to the outlying stations in a manner which will be apparent as the description proceeds. A circuit is also closed from ground on conductor 69 through the winding of relay B and resistance 74 in parallel, 65 resistance 75 to battery on conductor 72 thereby causing relay B to operate and at its armature 76 apply ground to conductor 77 from whence the circuit is traced through the winding of relay C, resistance 78 to battery on conductor 72. Relay C operates over the circuit just de-

scribed and at its armature 79 completes the circuit from the input transformer 6 of the microphone amplifier by way of conductor 81, operated contacts 82 of the key TK, conductor 83, make contact and armature 79 of relay C, conductor 84, winding 2 of relay A, conductor 85, contacts 86 of the key TK, conductor 87 and thence to the input of transformer 6. The tone induced in winding 2 of relay A is thus amplified by the amplifier circuit MA and transmitted to the outlying stations during the time that relay C is operated. When relay C moved its armature 88 into engagement with the make contact thereof, a short circuit was placed across the winding of relay B, causing relay B to release and at its contact 89 short circuit the winding of relay C, thereby releasing relay C and interrupting the tone circuit at its armature 79. The release of relay C at its armature 88 removed the short circuit from relay B which immediately 20 reoperates and the cycle of operations just described is repeated at intervals causing an interrupted tone signal to be received by the loud speakers at the outlying stations. Since the release of relays B and C is caused by short circuiting their respective windings, these relays release slowly and a slow rate of interruption of the tone signal is thereby obtained, the resistance 74 in parallel with the winding of relay B assisting in slowing the action of this relay. 30

When the disconnect signal is received at the outlying station, the subscriber or attendant opens the switch 53 thereby disconnecting power from the subscriber's power supply and amplifier units. When the tone signal has been transmitted for a sufficient length of time, the key TK is moved to the "off" position, thereby releasing the flash relays in the main and repeating stations and in the outlying stations. The restoration of the key TK to the "off" position also releases relay S and causes the interrupted tone generator at the main station to cease operating. 35

Whenever relay S operated to connect the input of the buffer amplifier BA to the microphone amplifier, it also established a connection by way of conductors 91 between the microphone amplifier and the repeater amplifier RA2, located preferably in or relatively near the main station, for amplifying the received signals and passing them along to one or more line coupling 40 units LC for distribution to outlying stations over the outgoing conductors 92, two such outlying stations being shown on the drawings connected to each pair of outgoing conductors 92, although it will be understood that the number 45 of outlying stations connected to each pair of conductors may vary within wide limits without impairing the efficiency of the system. Furthermore all the outlying stations may be located near the line coupling units LC or remote therefrom or some may be located near the line coupling units and others remote therefrom on the line circuit comprising a pair of conductors 92. In order that each station may receive the same 50 strength of signals irrespective of its location with respect to the line coupling unit or other outlying stations on the same subscriber's loop, the slip connections 37 are brought into engagement with different ones of the taps 36 of the transformer 35 of the line coupling unit and the balancing resistances 38 are adjusted until a 55 uniform strength of signal is received.

Whenever a news flash is to be transmitted, the relay NF, Fig. 2, is operated and at its armature 93 applies battery to conductor 94 extend-

ing to each of the line coupling units of Fig. 2, thereby to control the operation of the subscriber's flash relays **SFL** of the outlying stations connected thereto.

The repeater amplifier **RA2** is similar in all respects to the repeater amplifier **RA1**, shown on Fig. 3 of the drawings and receives the filament and plate current necessary for the operation of the amplifier tubes from a power supply unit **PS**, the circuit details of this power supply unit being shown diagrammatically on Fig. 1. The repeater amplifier unit at the repeater station **RS1** receives power for operation from the power supply unit **PS1**, Fig. 3, in a manner similar to the repeater amplifier unit **RA2**. The filaments of the amplifying tubes of the microphone and buffer amplifiers are shown connected by the conductors **96** to terminals **1** and **4** of the transformer **95** of the power supply unit, the other side of the transformer being connected to a source of current. The heater filament of the tubes of the repeater amplifiers **RA1** and **RA2** are connected to terminals **2** and **3** of the power supply unit since it may be desirable under certain conditions to employ tubes in these amplifiers having different characteristics from those used with the microphone and buffer amplifiers.

The method of adjusting the output level of the microphone amplifier is as follows: With the key **TK** moved to the "off" position and the plug **3** inserted into the jack **4**, an artificial load **67** is connected across the output of the microphone amplifier and the meter **DB** is connected in parallel with this load, thereby placing the circuit in condition for adjustment of the microphone amplifier. The microphone is actuated by the human voice or other sound producing means and the output level of the microphone amplifier is indicated by the decibel meter **DB**, during which time the variable resistance **97** across the input of transformer **6** is adjusted until a suitable output level from the amplifier **MA** is obtained. During the foregoing operation relay **S** was unoperated and at its armature **18** connected a shunt across the input winding of the transformer **16** of the buffer amplifier **BA** and repeater amplifier **RA2** to prevent any extraneous signals from being transmitted to the outlying stations. After the foregoing adjusting operation has been completed, key **SK** is operated causing relay **S** to operate and remove the artificial load **67** from the microphone amplifier and substitute therefor the buffer amplifier **BA** and repeater amplifier **RA2**, thereby operatingly connecting the microphone to the outlying stations.

The input side of transformer **16** supplying the buffer amplifier is connected to an attenuator which, in the illustrative embodiment of the invention, may comprise the variable resistance units **98**. This attenuator is adjusted to obtain the proper output level on the conductors **23** and **24** extending to the repeater station **RS**. The input to the repeater amplifiers **RA1** and **RA2** is connected to an attenuator **99** to control the output level of these amplifiers in accordance with the number of line coupling units connected thereto. The output transformer **31** of these repeater amplifiers, as heretofore stated, is provided with a series of taps **32** and slip connections **33** adapted to be connected thereto for matching the impedance of the line coupling units to the impedance of the repeater amplifiers. The impedance of each subscriber's loop **75** is matched to the impedance of the associated

line coupling unit **LC** by the slip connections **37** and taps **36** of the transformer **35** and by adjusting the resistances **38** so that the line coupling unit presents the same impedance to the amplifier thus providing an arrangement whereby a uniform distribution of signals to the several subscriber's loops is obtained. In the event that no subscriber's stations are in connection with a particular line coupling unit, the wires **39** are connected together and an artificial load comprising the resistances **38** is thus connected to the line coupling unit whereby the impedance of the line coupling unit may be brought into matched relationship with the repeater amplifier.

Referring now to the subscriber's amplifier circuit, Fig. 4, the input side of the input transformer **43** thereof is connected to a potentiometer **42** for controlling the volume level of the loud speaker **48**. The subscriber's amplifier is adapted to be operated from either alternating or direct source of current, the arrangement shown employing the tubes **44** and **45** in push-pull combination for actuating the loud speaker. When connected to a source of direct current, the subscriber's power supply unit should be so connected that conductor **180** is in circuit with the source of positive potential. The buffer amplifier **BA** is employed to increase the output level of the microphone amplifier in order that the signals received at the repeater station **RS**, which may be located at a considerable distance from the main station, will be comparable in order of magnitude with the signals received by the repeater station **RA2**. The specific circuit arrangement including the pairs of conductors **23** and **24** is such that a circuit failure of either of these pairs of conductors, resulting for example from a storm or physical injury to the conductors, does not permanently disable the system, as the repeating station **RS** may receive signals over the other pair of conductors by the operation of the switch **25**. Whereas in the event that that portion of the system controlled by the conductors **23** and **24** should become inoperative for any reason, the repeater amplifier **RA2** would continue to operate and the service furnished the subscribers served thereby would be uninterrupted.

While the invention has been described in detail with respect to a certain preferred example thereof which gives satisfactory results, it will be understood by those skilled in the art after understanding the invention that various changes and modifications may be made without departing from the spirit and scope of the invention and it is intended therefore in the appended claims to cover all such changes and modifications.

What is claimed as new and desired to be secured by Letters Patent of the United States is:

1. In a system of the character described including a transmitting station and a plurality of receiving station amplifiers, a communication channel interconnecting said transmitting station and said station amplifiers, said transmitting station having means for transmitting over said channel signals comprising a composite program of different items of information and having means for causing special selecting signals to accompany the signals comprising certain of said items of the composite program transmitted, loud speaking receivers associated with said amplifiers, said loud speaking receivers being normally disconnected from said amplifiers, and means at each receiving station responsive to said special

signals for operatively connecting the loud speaking receiver with the amplifier to cause said loud speaking receiver to respond to the signals comprising said certain items of information.

5 2. In a system of the character described, the combination of a transmitting station, a receiving station including an amplifier and a loud speaking receiver, a communication channel interconnecting said transmitting and receiving stations, said transmitting station having means for transmitting over said channel signals comprising a composite program of different items of information and having means for causing special selecting signals to accompany the signals comprising certain of said items of the composite program transmitted, and means in said receiving station controlled by said special signals transmitted over the communication channel for operatively connecting the loud speaking receiver to the amplifier to selectively reproduce said certain items of information.

3. In a system of the character described, the combination of a main transmitting station including a signal generating device for transmitting a composite program of different items and manipulative means for causing special selecting signals to accompany the signals comprising certain of said items, a plurality of repeater stations connected to said main transmitting station for repeating the signals generated by the signal generating device including signal means responsive to the special signals under control of said manipulative means, a plurality of outlying stations connected to said repeating station each including an amplifier and a loud speaking receiver, switching means in each of said outlying stations controlled by the signal means in said repeating stations to selectively connect said loud speaking receivers with the amplifiers in accordance with the operation of said manipulative means at the main transmitting station.

4. In a news disseminating system for stocks and the like, the combination of a main transmitting station including a signal generating device and manipulative means, an amplifier connected to said signal generating device, a plurality of pairs of outgoing conductors, a repeater station including means for connecting any pair of outgoing conductors to the repeating station and a signal device at said repeating station controlled by said manipulative means over the outgoing conductors, a plurality of line coupling units connected to said repeating station each having a plurality of outlying stations connected thereto and including means controlled by said signal device at the repeating station for signaling the outlying stations, an amplifier and loud speaking receiver at each outlying station, and a switching device for operatively connecting said loud speaking receiver to the amplifier under control of the signal received from said line coupling unit in accordance with the operation of said manipulative means.

5. In a system of the character described including a main station and a plurality of outlying stations, a transmitter and manipulative means included in the main station, an amplifier operatively associated with said transmitter and said manipulative means, a repeater station intermediate said main station and said outlying stations including a signal device, a transmission circuit comprising a plurality of outgoing conductors interconnecting said amplifier and the repeater station, means including a phantom circuit for actuating said signal device at the repeating sta-

tion under control of said manipulative means, and means in each of the outlying stations actuated by said signal means for rendering the outlying stations selectively responsive to audibly reproduce signals received from said transmitter at the main station.

6. In a system for simultaneously receiving information comprising quotation signals and news flashes at a plurality of outlying stations from a source of signals at a main station, the combination of transmitting means including a manipulative device at the transmitting station operable in accordance with the news flashes to be transmitted for causing special selecting signals to accompany said news flashes, a plurality of line circuits connecting said main station with the outlying stations, an amplifier including a device for audibly reproducing signals received from the main station over the line circuits, and means at each outlying station controlled by the manipulative device and said special signals for establishing a circuit connection between said signal reproducing device and the amplifier whereby the signal reproducing device is actuated by said transmitting means to reproduce the news flashes and remain unresponsive to other quotation signals received.

7. In a system for disseminating information regarding stock and news items, the combination of a main station including a transmitter and a manipulative device operable in accordance with the news items to be transmitted for causing special selecting signals to accompany said news items, a plurality of outlying stations each comprising an amplifier and a loud speaking receiver normally disconnected from said amplifier, a plurality of transmission channels interconnecting said transmitting station and the outlying stations, a first means settable at will for bringing the loud speaking receiver into operative relationship with the amplifier whereby all of the signals received from the main station are reproduced by the loud speaking receiver and a second means effective when the said first means is not operated to bring the loud speaking receiver into operative relationship with the amplifier selectively under control of said manipulative device and said special signals.

8. In a system of the character described including a main station and a plurality of outlying stations, means including an amplifier at the main station for transmitting signals representative of stocks or other items and manipulative means, means in each of the outlying stations for selectively and audibly reproducing signals from the main station under control of said amplifier and manipulative means, a generating device at the main station for automatically transmitting at periodic intervals a special disconnect warning signal, and means for connecting said device to the amplifier at the main station to cause said special signal to be audibly reproduced at each of the outlying stations.

9. A wired news disseminating system comprising means for transmitting signals comprising a program of news items, a receiving station comprising an amplifier and a loud speaking receiver, a communication channel interconnecting said transmitting means and said receiving station, means for sending special selecting signals over the channel to accompany certain items of said program, and means at the receiving station responsive to said special signal for operatively connecting the loud speaking receiver to the amplifier.
